UNITED STATES PATENT OFFICE.

MARIE H. WIECHMANN, OF NEW YORK, N. Y.

HOSIERY.

Application filed August 19, 1920. Serial No. 404,614.

To all whom it may concern:

Be it known that I, MARIE H. WIECHMANN, a citizen of the United States, residing at New York, in the county of New York, State of New York, have invented certain new and useful Improvements in Hosiery; and I do hereby declare the following to be a full, clear, and exact description of the invention, such as will enable others skilled in the art to which it appertains to make and use the same.

This invention relates to improvements in hosiery, and more particularly ladies' hosiery. The improved hosiery of the present invention is of pleasing appearance, is adapted for the attachment of the garters thereto without injury, insures added comfort to the wearer, and presents other advantages, hereinafter more fully set forth.

In ladies' hosiery, as commonly made, it is customary to provide a wide hem at the upper end thereof in order to provide an increased thickness and added strength for the attachment of the garters. Even with the double thickness thus provided, however, the garters place a considerable strain upon the fabric of the stocking at the place where they are secured, and this not infrequently results in the breaking of one or more of the threads or yarns of the stocking, with resulting "running," which may prevent the further wearing of the stocking, or give to it an objectionable, unsightly appearance. In order to reduce to a certain degree this danger of injury to the stocking, it is common to provide garters with extra large knobs and clasps so that an increased amount of the stocking fabric can be gripped thereby; but this is likewise objectionable for the reason that the large knobs of the garter protrude in an unsightly manner, especially in the summertime and with thin garments. Garters of this character may even be annoying to the wearer when seated, because of their size and because of the customary use of two or more garters attached at different places around the top of the stocking.

The present invention relates to an improved form of hosiery which makes possible a very substantial saving in the amount of fabric commonly required, which enables garters of comparatively small size to be secured thereto with the required firmness, and which will equalize the strain placed upon the stocking by the garters, with resulting decrease in the strain placed upon

the stocking as a whole at any one place, and correspondingly increased comfort to the wearer.

The improved hosiery of the present invention are provided at their upper ends with a series of loops, through which the garters are adapted to be passed and to which the garters are adapted to be secured, which loops are made, for example, by knitting, crocheting, weaving, etc., so as to provide a construction of proper strength and having an elasticity comparable with that of the stocking itself, so that the upper edge of the stocking can be stretched to the desired extent and will accommodate itself, because of its elasticity, when worn. The material forming the garter loops is made integral with or secured to the upper edge of the stocking, which can be sufficiently reinforced for this purpose, and which will in turn be strengthened and reinforced by the manner in which the loops, and the material of which they are made, are secured.

Inasmuch as the improved hosiery of the present invention have garter loops thus provided at their upper ends, it becomes unnecessary to provide a wide hem for the attachment of the garters, and this hem can therefore be omitted, or made much narrower, thereby effecting a substantial economy in the amount of material required for the completed hosiery.

The invention will be further described in connection with the preferred embodiments thereof illustrated in the accompanying drawing, but it is intended and will be understood that the invention is illustrated by, but is not limited to, the specific embodiments so illustrated and described.

In the accompanying drawing, Fig. 1 shows, in a somewhat diagrammatic manner, the upper end of a stocking embodying the invention; Fig. 2 is an enlarged view of part of the stocking of Fig. 1; Fig. 3 is an enlarged sectional view taken on the line 3-3 of Fig. 2; Fig. 4 is a diagrammatic or skeleton view illustrating one mode of forming the garter loops; Fig. 5 shows a modified embodiment of the invention; and Fig. 6 shows a still further modified form of the invention.

The stocking 1 may be of cotton, silk, or other material, and may be woven or knitted in the usual way. Instead of providing a wide hem at the upper end thereof, for attachment of the garters, this hem is omitted

or reduced to a very narrow hem, such as indicated at 2. Added strength can be secured by underlying a flexible cord or thread 3 before the narrow hem 2 is turned and secured. The cord or thread 3 should have a sufficient degree of elasticity to permit the upper end of the stocking to be stretched to the necessary extent, as when the stocking is put on or taken off.

10 Secured to the upper edge of the stocking are a series of loops 4, spaced a short distance apart, and providing loops for the attachment of the garters. While these loops need not extend around the entire top 15 of the stocking, yet it is desirable for various reasons, that they should so extend. For example, corsets are commonly provided with two or three garter straps at each side, so that these can be secured to the stocking 20 at different places around the top of the same, to distribute the strain, and more uniformly support the stocking and hold it in place. Since hosiery must be interchangeable and capable of being worn on either 25 the right foot or the left, this requires that the garter shall be attachable either on one side or the other, and at various places around the top of the stocking. So also, the provision of a series of loops extending 30 entirely around the stocking, at suitable distances apart, adds to the pleasing appearance of the stocking and gives it a desirable finished appearance.

As illustrated in Figs. 1 to 4, the loops 4 35 are made by securing a series of rows of stitching or of crocheting, knitting or weaving, around the reinforced top of the stocking. As illustrated in Fig. 4, a series of stitches 8 may thus be made around the tops 40 of the stockings, the thread or yarn, at intervals, forming a large loop 4, and, between these loops, forming a series of small loops each secured to the top of the stocking. The second series of stitches or loops 45 9 is then attached to the first series, to strengthen and reinforce the same, and a third series of loops 10 is then applied, this series extending back and forth around the loop 4 three times, thus giving added reinforcement. The loops thus made, e. g., by 50 crocheting or knitting, serve to reinforce the loops 4 and to distribute the strain due to the attachment of the garters through these loops. That is, instead of the strain being 55 taken up entirely by the ends of the loops 4, at their inner edges, this strain is distributed over a considerable portion of the top of the stocking next adjoining the loop, this distribution being promoted by the manner 60 in which the loops and intervening reinforcement are formed. The inner series of loops 9, secured around the inner loop 8, may thus be more closely arranged, as indicated at 5 in Figs. 2 and 3, while the 65 outer rows, indicated at 6 in Figs. 2 and 3,

may be of coarser weave or knitting. It is desirable to have a substantial width of the material forming the loop so that this material will be gripped and held between the two parts of the garter clasp, and the 70 garter thereby kept from slipping. This arrangement further assists in more uniformly distributing the garter strain around the top of the stocking.

In the construction of Fig. 5, the loops 75 are formed by knitting, crocheting, etc., in a manner somewhat similar to that indicated in Fig. 4. Thus, the inner row of stitches 15 passes around the top of the stocking and the inside of the loops 23, and the loops are 80 reinforced by a plurality of additional rows of stitches indicated at 16, 17 and 19, while the stocking between the loops is further reinforced by a second row of stitches 18. In forming the loops and reinforcement, the 85 inner row of stitches may be applied to the stocking 21, and formed into loops 23 at regular intervals, and the second row of stitches 18 may then be applied and secured to the first row, passing around the loop 90 once to form the row 16, thence back to form the row 17, and again in the reverse direction to form the outer row 19, after which the row continues to the next loops. This 95 arrangement assists in distributing the strain applied to the loop so that it is taken up by a considerable portion of the top of the stocking.

In the construction of Fig. 6, the garter loops are formed integral with the stocking 100 itself, for example, by knitting or crocheting. The stocking 21 may thus be provided with an upper portion of thicker weave to form a reinforced upper end, and the loops 23 may be formed by weaving or knitting 105 a plurality of rows of stitches 25 which extend around the loops as indicated at 24. This arrangement also provides for distributing the strain of the garter over a considerable 110 portion of the top of the stocking.

The illustrations of Figs. 5 and 6, as well as those of the other figures, have been somewhat exaggerated for purposes of illustration, inasmuch as the knitting and similar operations are well understood by those 115 skilled in the art so that detailed description and illustration is unnecessary.

The mode of attaching a garter to the stocking is illustrated in Fig. 1, that is, by inserting the knob 27 of the usual garter 120 through the loop 4 and securing the clasp 26 to the knob after it has passed through the loop. The material of the loop is thus clamped between the clasp 26 and the back 125 part of the garter carrying the knob 27, in the manner above described. The fabric 28 of the garter is preferably adjustable (by means not shown), so that the garter may extend to the desired length to permit 130 attachment to the loops of the stocking.

When two or more garters are secured to the stocking, at different places around its upper end, the strain or pull upon the stocking will be distributed, and this pull or strain will in turn be taken up by a considerable portion of the top of the stocking at and near the upper loop or loops to which the garters are attached.

The present invention makes possible the use of a smaller garter clasp than is commonly used, inasmuch as such a smaller clasp can with equal if not greater facility be secured to the garter loops than can a larger clasp. The improved hosiery of the present invention thus makes possible the use of less unsightly and less annoying garter and garter clasps, while nevertheless avoiding the objections which commonly prevent such clasps from being used.

In addition to the garter loops, similar to those above described, it will be evident that the upper ends of the stocking can be given a more finished and pleasing appearance by knitting or crocheting between the loops around the stocking. It will be evident that any such knitting or crocheting should be elastic to a degree comparable with that of the stocking itself.

By making the loops of a different color of yarn from that of the stocking, it is possible to add to the pleasing appearance of the stocking, as by using a color of yarn which will contrast with that of the stocking itself.

I claim:—

1. A stocking provided with a hem at the top thereof, and having a garter loop fixedly united with the top edge of the hem, and reinforcing means along the hem of the stocking.

2. A stocking provided with a hem at the top thereof, and having a garter loop fixedly united with the hem above the lower edge of the hem, and reinforcing means along the hem of the stocking.

3. A stocking having a narrow hem and having a reinforcing elastic cord enclosed therein, and a series of garter loops secured to the upper edge of the hem and to the cord by stitching, each of said garter loops comprising a series of rows of stitches and being so secured as to distribute the strain of the garter over a considerable portion of the upper edge of the stocking.

4. A stocking provided with a hem at the top thereof, having continuous reinforcing means along the hem, and a garter loop fixedly united to the hem and said reinforcing means.

5. A stocking provided with a hem at the top thereof, having continuous reinforcing means along the hem, and a garter loop fixedly united with the hem.

6. A stocking provided with a hem at the top thereof, and having a series of garter loops fixedly united with the hem, and reinforcing means along the hem of the stocking between said garter loops.

7. A stocking having a hem at the top thereof and having at least one garter loop permanently associated with the hem above the lower edge of said hem, and stitches arranged along the hem of the stocking and connected to either side of said loop so that the strain of the garter is distributed over a considerable portion of the upper edge of the stocking.

In testimony whereof I affix my signature.

MARIE H. WIECHMANN.
